UNITED STATES PATENT OFFICE

2,179,572

VENETIAN BLIND

Amos Bowman, Chicago, Ill.

Application September 25, 1936, Serial No. 102,457

3 Claims. (Cl. 156—17)

This invention relates to Venetian blinds, and more particularly to such a blind that is of great strength and so attached to a window as to be burglar-proof.

5 It is the general object of my invention to provide a blind of the Venetian type, constructed of heavy materials and arranged when installed to be locked in open or extended position so as to protect the window from being entered such as 10 by burglars or the like.

Another object of my invention is to provide such a Venetian blind that is simple, practical and efficient in operation.

A further object is to provide a Venetian blind 15 construction that is inexpensive to manufacture and easy to install and operate.

Other objects and advantages will be apparent and be brought out more fully in the following specification, reference being had to the accompanying drawings wherein:

Fig. 1 is a view of the interior of a window provided with a blind embodying my invention.

Fig. 2 is a sectional elevation taken along the line 2—2 of Fig. 1.

25 Fig. 3 is an enlarged view of the same taken along the line 3—3 of Fig. 1.

Fig. 4 is a sectional view taken along the line 4—4 of Fig. 3.

30 Fig. 5 is a fragmentary sectional view taken along the line 5—5 of Fig. 3 illustrating the locking mechanism.

Fig. 6 is a fragmentary view illustrating a feature of the operating mechanism; and

35 Fig. 7 is a fragmentary view illustrating a modification of the structure shown in Fig. 4.

Referring more particularly to the drawings, and especially to Figs. 1 and 2, I show a window 10 of the display type such as a store window having the usual glass pane 11 set between an 40 upper front wall 12 and a lower front wall 13, the ceiling of the room being illustrated at 14, there being a display cabinet 15 located immediately 45 interiorly of the window, the cabinet having a floor or sill 16, a rear wall 17, side walls 18 and a top wall 19. The Venetian blind comprising my invention is indicated generally at 20 and includes an upper housing 21 (Fig. 3) which consists of a divided chamber 22 having an upper chamber 22a and a lower chamber 22b, a front wall 23, a rear 50 wall 24 and end walls 25. A frame member 26 separates chambers 22a and 22b and is provided with pairs of chain apertures 27 and cable apertures 28. A channel member 29 is suitably secured to floor or sill 16 and is so constructed 55 as to have flared, flanged portions 30. A pair of

circular flanged members 31 are secured to channel 29 by bolts 32 or otherwise, and each provides a base for a stanchion 33 which in the preferred form is shown as consisting of a pipe of substantial strength. A lock screw 34 holds stanchion 33 5 to flange 31. A similar circular flange 35 is secured as by bolts 36 to frame member 26, a lock bolt 37 being provided for attachment of flange 35 to stanchion 33.

A horizontal shaft 38 is mounted at each end 10 in flange bearings 39 secured to end walls 25 and a pair of sprocket segments 40 are rigidly attached to shaft 38. A pair of chains 41 are carried by sprocket segments 40 and these chains consist of a plurality of plain links 42 and supporting links 15 43, links 43 having lugs 44, opposite pairs of which are attached to and provide support for a link member 45. A plurality of louvres 46 are supported by link 45 of each chain 41, louvres 46 preferably consisting of strong material such as 20 sheet steel, the edges 47 of which are turned down to form flanges. The louvres are provided with elongated apertures 48, each for the reception of stanchion 33, and elongated apertures 49 each for the reception of an operating cable to be described hereinafter. The ends of each chain 41 are secured to straps 50, the opposite ends of which are secured to a channel member 51 which may be considered as being one of the louvres. Channel member 51 has flanged edges 52 which 25 are adapted to rest between flanges 30 of the channel member 29 when the blind 20 is in an extended position, and is provided with apertures 53 for the reception of flange 31 and stanchion 33. Channel 51 is further provided with an aperture 35 54 under each aperture 49 and a pair of lugs 55 are located adjacent aperture 54 on the lower side of channel 51 carrying a pin 56 adapted for the attachment of one end of a cable 57 which extends through apertures 49 and 54 of the louvres. The 40 cable 57 is attached at its upper end to a drum 58 secured to a shaft 59 mounted in bearings 60, secured to end walls 25. A sprocket 61 is secured to shaft 59 and carries a chain 62 adapted to be passed over a pair of idler sprockets 63 mounted 45 on a bracket 64, suitably secured to ceiling 14. A sprocket 65 mounted on a shaft 66 is carried by a bearing bracket 67 secured to the floor or sill 16, and an operating crank 68 is provided for shaft 66. A drum 69 is secured to shaft 38 and 50 an operating cable 70 is secured thereto as by clamp bolt 71 and passes over and is similarly attached to a drum 72 carried by a shaft 73, mounted on an arm 74 attached to bracket 64. A cable 75 is similarly secured to drum 72 and to a 55

drum 76 carried by a shaft 77 which is mounted in a bracket 78 on floor or sill 16 and a crank 79 is provided for the operation of shaft 77.

In Fig. 5 I show in detail one of a pair of locks 80, each of which is provided with a housing 81 suitably secured to channel member 29, the housing 81 containing a solenoid 82 having an armature 83. The housing 81 has a wall 84 provided with an aperture 85. The lock 80 has a lock bolt 86 which is secured to armature 83 and extends through an aperture 87 in an end wall 88 of housing 81. A collar 89 is secured to armature 83 and a spring 90 is positioned between collar 89 and wall 84. The bolt 86 is provided with the usual beveled face 91. A keeper 92 is attached to the under side of channel 51 as by bolts 93 and has a beveled edge 94 for cooperative engagement with beveled face 91 and the lock bolt 86.

I show an operating battery 95 for solenoid 82, 20 being connected thereto by a push-button switch 96, there being the usual circuit wires 97, 98 and 99.

In Fig. 7 I show a modification of the stanchion 33 in the form of a channel 100 which may be desired if greater strength is required than could be provided with a pipe member. In this case the apertures 48a in the louvres would preferably be rectangular.

The operation of my invention should be apparent from the foregoing description, the louvres of the blind being collapsible when raised by the operation of crank 68 which actuates cable 62, drums 58 and cables 57 connected to the bottom louvre 51. When the louvres are let down or extended, the channel louvre 51 will be dropped into inter-fitting position with fixed channel 29 and the keeper 92 will engage lock bolt 86 which will cause the blinds to be locked in this extended position. The louvres 46 will be held in this position by virtue of their support on chains 41. The stanchions 33 will effectively prevent the displacement of the louvres from this position in any unauthorized manner such as a burglarizing operation, and the contents of the store or window will be effectively protected by the blinds as will be clear. When it is desired to raise the blinds the operation of push-button 96 will actuate solenoids 82 to release the keepers 92 of the channel louvre 51, and the blinds may be raised by the operation of crank 68. The louvres are adjustable as to angular position by the rocking

of shaft 38 by cables 70 and 75 from crank 79 in the well-understood manner.

While I have illustrated and described the preferred form of construction for carrying my invention into effect; this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. The combination with a window, of a Venetian blind comprising a pair of stanchions fixedly secured at both ends adjacent said window, a plurality of louvres slidably mounted on said stanchions, the lowermost louvre comprising a channel bar having its flanges extending downwardly, 15 a keeper arranged within said channel bar and a lock arranged adjacent the bottom of the window and adapted to engage said keeper and be encased by said channel member when in lowermost position, substantially as described.

2. The combination with a window, of a Venetian blind comprising a pair of stanchions fixedly secured at both ends adjacent said window, a plurality of louvres slidably mounted on said stanchions, the lowermost louvre comprising a 20 channel bar having its flanges extending downwardly, a keeper arranged within said channel bar and a lock arranged adjacent the bottom of the window and adapted to engage said keeper and be encased by said channel member when in lowermost position, substantially as described.

3. The combination with a window, of a Venetian blind comprising a pair of stanchions fixedly secured at both ends, a plurality of louvres slidably mounted on said stanchions, the lowermost louvre comprising a channel bar having its flanges extending downwardly, a channel bar 30 fixed adjacent the lower ends of said stanchions and having its flanges extending upwardly to receive the lowermost louvre between them, and locking means enclosed by said channel bars, substantially as described.

AMOS BOWMAN.
